UNITED STATES PATENT OFFICE.

CHARLES G. ALLAN, OF DENVER, COLORADO.

DESIGN FOR A FLAG.

Application filed March 10, 1922. Serial No. 1,101. Term of patent 3½ years.

To all whom it may concern:

Be it known that I, CHARLES G. ALLAN, a citizen of the United States, residing at the city and county of Denver and State of Colorado, have invented a new, original, and ornamental Design for a Flag, of which the following is a specification, reference being made to the accompanying drawing, forming a part hereof,

The drawing is an elevation of a flag showing my new design.

I claim:

The ornamental design for a flag as shown. In testimony whereof I affix my signature.

CHARLES G. ALLAN.
